(57) **CLAIM**

The ornamental design for a patterned inlay strip, as shown and described.

DESCRIPTION

This application is being filed with application for U.S. Letters Patent Ser. No. 12/540,221, entitled Stone Article With Patterned Trim, which is hereby incorporated in its entirety by reference herein.

FIG. 1 is a front perspective view of a patterned inlay strip showing my new design. The broken lines are for illustrative purposes only and form no part of the claimed design.

FIG. 2 is a rear perspective of the patterned inlay assembly shown in FIG. 1;

FIG. 3 is a front elevation of the patterned inlay assembly shown in FIGS. 1 and 2, with the rear elevation being a mirror image thereof;

FIG. 4 is a top view of the patterned inlay assembly shown in FIGS. 1-3, with the bottom view being a mirror image thereof; and,

FIG. 5 is a side elevation of the patterned inlay assembly shown in FIGS. 1-4, with the opposite side elevation being a mirror image thereof.
